SAFETY CLIP

Joseph L. Mancini, Baltimore, Md., assignor to
General Motors Corporation, Detroit, Mich., a
corporation of Delaware

Application June 8, 1944, Serial No. 539,301

2 Claims. (Cl. 85—5)

This invention relates to a clip designed for use in temporarily holding together two or more sheets of metal preparatory to riveting them together.

The essential novelty of the invention is the enclosing in a single housing of substantially all of the operative parts; making the clip much shorter than clips now in use; and using a pin-type of tool or pliers to operate the clip.

On the drawing:

Figure 1 is a perspective view of the clip applied to two superimposed sheets of metal.

Figure 2 is a side elevation of the clip applied to two sheets of metal and showing the pin-type of tool in the operative position to release or apply the clip.

Figure 3 is a view similar to Figure 2 but showing the tool released and the clip in position to hold the sheets of metal together.

Figure 4 is an enlarged sectional detailed view through the center of the clip and showing the released position of the plunger and pilot in dotted outline.

Figure 5 is an enlarged sectional detailed view substantially on the line 5—5 of Figure 4.

Figure 6 is an expanded view of the upper end of one of the plunger halves and the key and pin to hold the plunger halves together.

Referring to the drawing, the numeral 2 indicates the clip as a whole. In its applied position, the clip is adapted to hold two or more sheets 4 and 6 together while the operator or workman applies rivets to the mated openings 8 in the sheets of metal.

Referring to Figure 4, the clip comprises the outer housing 10 which includes the cap 12 secured to the housing 10 by means of the flanges 14 and 16 and the solder 18. Inside the housing there is the outer compression coil spring 20 which rests at its lower end against the bottom of the housing and at its upper end it rests against a flange on a retainer 22.

The retainer 22 has a recess 24 and in the recess there is adapted to be received the head 26 of a plunger 28. The plunger 28 passes through an opening in the bottom of the recess and is formed into two halves 30 and 32, and these two halves are secured together at the head 26 by means of a key 34 and a pin 36 passing through an opening 38 in the key and being received in recesses 40 in the plunger halves 30 and 32. The lower ends of the plunger halves 30 and 32 project through an opening 42 in the bottom wall of the housing and are spread apart by means of a pilot

or spreader 44. Outside the housing 10 the plunger halves 30 and 32 are provided with the head portions 46 and 48 which together with the spreader 44 therebetween form a head indicated as a whole at 50. The head 50 prevents the plunger 28 from being retracted by the spring 20 into the housing through the opening 42.

The pilot or spreader 44 has lateral extensions or shoulders 52 at its upper part and between the extension 52 and the end of the retainer 22 a coil spring 54 is received. This spring is weaker than the spring 20, is not under compression in the position of Figure 4, and forces the pilot 44 out of the opening 42 in a ratio of 2:1 with reference to the distance the spring 20 forces the plunger 28 outwardly.

On the lower side of the extension 52 and between the extension and the bottom of the housing 10, a third coil spring 56 is positioned. This spring 56 is weaker than the spring 54 and retracts the pilot or spreader 44 into the housing.

At the upper part of the housing an inwardly directed flange 58 defines an opening at the top of the housing, and in this opening there is adapted to be received the pin 60 of a tool 62 in the form of a pair of pliers. The tool has a fork 64 which is adapted to straddle the clip and be received under the flange 14 on the housing. By pressing the handles 66 of the pliers together,

pin 60 will force the retainer 22 downwardly in the housing (when viewing Figure 4) and compress the springs 20, 54 and 56. In this position of the parts the head 50 will assume the dotted line position shown in Figure 4. The spring 54

is stronger than the spring 56 to cause the pilot 44 to be pushed part-way from the opening 42 to make a stiffer locating pin. In the dotted line position of the head 50 in Figure 4, the head halves 46 and 48 can approach each other to

enable the head 50 to be inserted through an opening such as 8 in the sheets of metal, and when the head 50 has been inserted through the opening and the tool released to the position shown in Figure 3, the spring 20 will force the

retainer 22 to the full line position shown in Figure 4, while the spring 56 will move the pilot or spreader 44 upwardly to the full line position shown. The head halves 46 and 48 will therefore be spread or forced apart by the spreader 44

and caused to grip the edge of the opening on the opposite side of the metal sheets 4 and 6 as shown in Figure 3, temporarily to hold the sheets together.

When it is desired to release the clip, the operator will apply the pliers as shown in Figure

2, and while the pin 60 has compressed the spring 20 the clip can be bodily lifted from the opening to enable a rivet to be applied therein.

It is obvious that as many clips as are necessary can be used properly to hold the metal sheets together while they are being riveted.

To disassemble the clip, the solder 18 can be fused which will release the cap 12. The spring 20 is then compressed and the spreader 44 pushed inwardly. The release of the spring 20 will now enable it to retract the plunger and pull the head 50 through the opening 42.

The clip of the invention has the advantage of having the parts inclosed in a housing and of being much shorter than clips used for similar purposes. This shortness of the clip enables the riveting mechanism to operate more freely, i. e., without interference by the clip.

I claim:

1. In a clip for temporarily fastening two sheets of metal together, a housing having openings in both ends, a plunger in the housing projecting from one end thereof, a retainer secured to said plunger in the housing, a coil spring in the housing between one end thereof and the retainer and constantly urging the plunger inwardly of the housing, said plunger being formed of two parts, a spreader between the parts, an extension on the end of the spreader, a coil spring in the housing between the extension and the retainer, a coil spring in the housing between the extension and the end of the housing, and a head on the projecting end of said plunger outside the housing, said retainer adapted to be pushed inwardly of the housing to force the headed end of the plunger away from the housing and away from the spreader therebetween to enable the halves of the plunger outside the housing to approach each other to enable the head to be inserted in mating openings in two overlapping sheets of metal, the release of said retainer caus-

ing the two-part head to be drawn toward the housing by the first mentioned spring and to be spread by the spreader, thereby causing the head to be retained on the side of the sheets opposite that to which the clip is applied temporarily to hold the sheets together.

2. In a clip for temporarily fastening two sheets of metal together, a housing having openings in both ends, a plunger in the housing projecting from one end thereof, a retainer secured to said plunger in the housing, a coil spring in the housing between one end thereof and the retainer and constantly urging the plunger inwardly of the housing, said plunger being formed of two parts, a spreader between the parts, an extension on the end of the spreader, a coil spring in the housing between the extension and the retainer, a coil spring in the housing between the extension and the end of the housing, and a head on the projecting end of said plunger outside the housing to approach each other to enable the head to be inserted in mating openings in two overlapping sheets of metal, the release of said retainer causing the two-part head to be drawn toward the housing by the first mentioned spring and to be spread by the spreader, thereby causing the head to be retained on the side of the sheets opposite that to which the clip is applied temporarily to hold the sheets together, said third mentioned spring being weaker than the second mentioned spring to enable the said second spring to force the spreader partway out of the housing when the retainer is pushed inwardly of the housing.

JOSEPH L. MANCINI.
